CLAIM

The ornamental design for an electric orbital sander, as shown and described.

DESCRIPTION

FIG. 1 is a perspective view electric orbital sander showing our new design;

FIG. 2 is top plan view thereof;

FIG. 3 is a bottom plan view thereof;

FIG. 4 is a left side view thereof;

FIG. 5 is a right side view thereof;

FIG. 6 is a front elevational view thereof; and,

FIG. 7 is a rear elevational view thereof.

In the drawings, the portions of the article shown in broken lines do not form any part of the claimed design.
